US0D1083220S

(12) **United States Design Patent** (10) **Patent No.:** **US D1,083,220 S**
(45) **Date of Patent:** **** Jul. 8, 2025**

(54) **COSMETIC APPLICATOR**

(71) Applicant: **ELC MANAGEMENT LLC**, Melville, NY (US)

(72) Inventor: **Yeon Jung Roh**, New York, NY (US)

(73) Assignee: **ELC MANAGEMENT LLC**, Melville, NY (US)

(**) Term: **15 Years**

(21) Appl. No.: **29/911,344**

(22) Filed: **Sep. 1, 2023**

(51) LOC (15) Cl. **28-03**

(52) U.S. Cl.

USPC **D28/7**

(58) **Field of Classification Search**

USPC **D28/4, 7, 9, 20, 76, 85**
